UNITED STATES PATENT OFFICE.

OLIVER P. SCOTT, OF TACOMA, WASHINGTON.

ELECTRIC HOT-AIR HEATER.

1,389,165.

Specification of Letters Patent. Patented Aug. 30, 1921.

Application filed September 1, 1920. Serial No. 407,391.

To all whom it may concern:

Be it known that I, OLIVER P. SCOTT, a citizen of the United States, residing at Tacoma, in the county of Pierce and State of Washington, have invented new and useful Improvements in Electric Hot-Air Heaters, of which the following is a specification.

This invention relates to an electric hot air heater.

The object of the present invention is to provide a simple, practical and efficient electric hot air heater of strong and durable construction adapted to be readily installed beneath the floor similar to the radiator of an ordinary hot air furnace and capable of giving a positive circulation of air through it and of taking cold air from the floor and heating the same and effectively maintaining it at a comfortable temperature.

A further object of the invention is to provide an electric heater of this character in which there will be no loss of moisture or oxygen from the ordinary air and over which the heating coil may be operated at a relatively low temperature so that it will not glow and scale or take up moisture or oxygen from the air passing through the heater.

With these and other objects in view, the invention consists in the construction and novel combination of parts hereinafter fully described, illustrated in the accompanying drawings and pointed out in the claims hereto appended, it being understood that various changes in the form, proportion, size and minor details of construction, within the scope of the appended claims, may be resorted to without departing from the spirit of the invention or sacrificing any of the advantages thereof.

In the accompanying drawings, in which like numerals of reference designate corresponding parts in the several figures:

Figure 1, is a vertical sectional view of an electric air heater constructed in accordance with this invention.

Fig. 2 is a horizontal sectional view of the same.

Fig. 3 is a perspective view of the outer casing and the radiator or grating.

Fig. 4 is a detail perspective view of the sectional inner core.

Fig. 5 is a similar view of the supporting base.

In the accompanying drawings in which

is illustrated the preferred embodiment of the invention, the electric air heater comprises in its construction, an outer rectangular casing 1 secured at an opening 2 in a floor 3 between two of the supporting joists 4 and composed of vertical sides and a horizontal bottom 5. The outer casing which may be of any other preferred form or construction is covered at the top by a radiator or grating 6 similar to the radiator or grating of an ordinary hot air furnace. The radiator or grating is secured to the floor and the outer casing 1 may be fastened to the radiator or grating 6 in any suitable manner. Within the outer casing and in spaced relation with the walls thereof, is an inner wall or casing 7 preferably of cylindrical form but it may of course be of any other desired configuration and it is preferably relatively thick and provided with an interior packing 8 of asbestos or other suitable material adapted to prevent heat from the space inclosed by the inner wall from passing through the latter heating the air in the space 9 surrounding the inner wall or casing. The inner wall or casing which is hollow to receive the asbestos packing, may be made of any suitable material and it is provided at its outer face with an extension or upper section 10 which is relatively thin and which extends entirely to the grating or register 6 to prevent passage of air across the top of the inner wall or casing. The inner wall or casing which is open at its top and bottom, is spaced from the bottom 5 to permit the cold air from the floor to pass downward into the space 9 and around the lower end of the inner wall or casing and upward through the space 11 inclosed by the said inner wall or casing which contains electrical heating means hereinafter described, whereby the air is heated within the inner wall or casing and is caused to rise and pass out of the radiator or grating and produce a positive circulation of air through the heater, and room or house.

The heating element comprises a hollow cylindrical core 12 and a heating coil 13. The core which is constructed of fire clay or similar refractory material is preferably made in two sections 14 to permit expansion and contraction without cooling stresses and the said core is provided with an exterior spiral groove 15 in which the wire of the heating coil is sealed to prevent slipping.

The wire of the heating coil is designed to be relatively long, viz. 150 ft. and in practice the coil will be maintained at a relatively low temperature and will not be caused to 5 glow and consume oxygen from the air passing through the heater or eliminate moisture from the air so that the heated air discharged from the heater will be in its normal moist condition. The terminals 16 of 10 the resistance coil are connected with feed wires 17 which extend through suitable insulators 18 of aluminum or other suitable material and any number of heating coils may of course be employed for providing 15 a heating element of the desired power.

The core of the heating element and the inner casing are mounted upon a base 19 of cast metal or other suitable material consisting of a circular central portion or disk 20 and radial arms 21 provided with depending feet 22 and having lugs 23 and 24 projecting from the upper edges of the arms and arranged to engage the core and the inner casing intermediate of the same for 25 preventing relative movement of the said parts of the base. The central circular portion or disk is provided with openings 25 to permit the air to pass upwardly through the core which will become highly heated and 30 which will retain heat for a considerable period after the current has been cut off. The outer casing 1 is provided with an opening 26 formed in one of the side walls, which side wall is equipped with a cover or 35 closure plate 27 adapted to operate as a damper and also to permit access to the interior of the outer casing for cleaning or other purpose. A central vertical rod or bolt 28 extends through the core and is provided 40 at its upper end with a head 29 and is threaded at the lower end for the reception of a nut 30. The central rod or bolt extends through an aperture 31 of the base and the head may be engaged with a horizontal bar 45 member 32 extending across the top of the inner casing and arranged upon the upper edge of the same but the central rod or bolt may engage the radiator or grating or head in any other desired manner as will be readily understood.

What is claimed is:—

1. An electric air heater of the class described including an outer casing, a radiator or grating extending across the top of the outer casing, an inner wall or casing arranged within the outer casing in spaced relation with the walls of the same and having a portion extending entirely up to the said casing to prevent air from passing over 55 the top of the inner wall or casing, and a heating element arranged within the inner wall or casing and adapted to cause a positive circulation through the heater.

2. An electric air heater of the class described including an outer casing open at the 60

top, a radiator or grating extending over the top of the outer casing, a hollow inner wall or casing arranged in spaced relation with the wall of the outer casing and having a non-heat conducting packing, said inner wall or casing being provided at the top with a relatively thin extension located adjacent the outer face of the said inner wall or casing and extending entirely up to the grating or register, a heating element arranged within the inner wall or casing, a base supporting the heating element, and the inner wall or casing, and a rod or bolt extending through the heating element and secured to the said base. 70

3. An electric air heater including an outer casing open at the top, a radiator or grating extending across the top of the outer casing, an inner wall or casing arranged within the outer casing and open at the top 75 and bottom, an electric heating element arranged within the inner casing in spaced relation with the same and comprising a sectional inner hollow core provided with exterior spiral grooves, and a heating coil arranged on the core and seated in the said grooves. 80

4. An electric hot air heater including an outer casing, open at the top and closed at the bottom for the discharge of heated air, 85 an inner wall or casing arranged in spaced relation with the outer casing and extending to the top of the same, a heating element having a hollow core and a base supported upon the bottom of the casing and receiving 90 the inner casing or wall and the core and having means for engaging and holding the same against relative movement. 95

5. An electric hot air heater including an outer casing, open at the top and closed at the bottom for the discharge of heated air, 100 an inner wall or casing extending to the top of the outer casing and arranged in spaced relation with the outer casing, a heating element having a hollow core, and a base receiving 105 the inner casing or wall and the core and having means for engaging and holding the same against relative movement, said base being also provided with legs supported upon the bottom of the outer casing. 110

6. An electric hot air heater including an outer casing open at the top for the discharge of heated air having a closed bottom, an inner wall or casing, a heating element arranged within the inner wall or casing and having a hollow core, a base supporting the inner wall comprising a central plate or portion, and radial arms having depending feet arranged upon the bottom of the outer casing, said arms being also provided with upwardly projecting legs engaging the core and the inner wall or casing for holding the same in its relative movement. 115

7. An electric hot air heater including an outer casing open at the top for the dis- 120

charge of heated air and having a bottom, an inner wall or casing, a heating element arranged within the inner wall or casing and having a hollow core, a base supporting the inner wall comprising a central plate or portion, radial arms having depending feet arranged upon the outer casing, said arms being also provided with upwardly projecting lugs engaging the core and the inner wall or casing for holding the same in its relative movement, and a cylindrical rod or bolt secured at its lower end to the said base.

In testimony whereof I have hereunto affixed my signature.

OLIVER P. SCOTT.
